(57) **CLAIM**

The ornamental design for a beverage cartridge component, as shown and described.

DESCRIPTION

FIG. 1 is a top, front perspective view of a beverage cartridge component showing our new design;

FIG. 2 is top, rear perspective view thereof;

FIG. 3 is a top, left side perspective view thereof, the top, right side perspective view thereof being identical to FIG. 3;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a top, front, left side, perspective, enlarged detail view of portion 8 shown in FIG. 1.

The dot-dash broken lines illustrate boundaries of the claim and form no part of the claimed design. The dash-dash broken lines illustrate portions of the beverage cartridge component that form no part of the claimed design.
